CLAIM

The ornamental design for a golf club cleaning device, as shown and described.

DESCRIPTION

FIG. 1 is a top front perspective view of the golf club cleaning device, showing the new design;

FIG. 2 is a bottom rear perspective view of the golf club cleaning device thereof;

FIG. 3 is a front elevation view of the golf club cleaning device, the rear elevation view being a mirror image thereof;

FIG. 4 is a right side elevation view of the golf club cleaning device, the left side elevation view being a mirror image thereof;

FIG. 5 is a top plan view of the golf club cleaning device thereof; and,

FIG. 6 is a bottom plan view of the golf club cleaning device thereof.

1 Claim, 3 Drawing Sheets
